REFRIGERATOR AND COMPARTMENT DEVICE THEREFOR

Filed July 11, 1927

Inventor
Otto Strufe
By Luther Johnson

UNITED STATES PATENT OFFICE.

OTTO STRUFE, OF DWIGHT, ILLINOIS.

REFRIGERATOR AND COMPARTMENT DEVICE THEREFOR.

Application filed July 11, 1927. Serial No. 204,728.

These improvements are primarily in refrigerators of the kind shown by my Patent 1,617,552 of February 15, 1927, according to which the refrigerator body has an extension adapted to pass into an opening in the building wall for "outside icing" and other advantages. The present improvements comprehend a special compartment preferably within the ice chamber of the refrigerator. Objects are to facilitate the storage and withdrawal of the food products; to provide convenient means for the delivery of food and other articles into the building from the outside, and for ready accessibility from the inside through a doorway of the refrigerator installation; to provide such means in close association with the heat-absorbing element—ice in the type of refrigerator shown; to provide means in the same connection whereby one making deliveries from the outside will not have access to the food products or whatever may be placed within the receptacle from the inside; to provide such advantages by means of a receptacle which may readily be removed as for cleaning or in special instances to accommodate a greater quantity of ice or other objects or articles in the ice box; and to provide for adjustability of partition means within the receptacle to vary the capacity of respective portions of the container. Other objects and advantages will appear hereinafter.

In the accompanying drawings, forming a part hereof, Figure 1 is a vertical section through a refrigerator of the kind shown in my said patent, this section being on the line 1—1 of Fig. 4; Fig. 2 is a horizontal section through the refrigerator as on the line 2—2 of Fig. 1; Fig. 3 is an enlarged section through the container or receptacle as on the line 3—3 of Fig. 4; Fig. 4 shows a fragmentary section of refrigerator parts and a cross-section through the container as on the line 4—4 of Fig. 1; Fig. 5 is a perspective of the open-top drawer which slides within the main housing part of the receptacle or container; Fig. 6 is an enlarged fragmentary sectional detail as on the line 6—6 of Fig. 5; Fig. 7 is a fragmentary view of the connection means for supporting the device as viewed from and in the direction of the arrows 7—7 of Fig. 4; and Fig. 8 is a fragmentary sectional view as on the line 8—8 of Fig. 7.

The refrigerator body 10 has an extension

11 passing through or substantially through the building wall 12 shown by dotted lines in Fig. 1. The ice compartment has an inner door 13 and an outer door 14. According to this type of refrigerator ice is delivered into the ice chamber through the door 14, and this same door 14 may be used by such tradesmen as the milkman and grocer for delivering their respective commodities.

It is customary for the housewife to pack around the ice in the ice chamber the bottles of milk, dishes containing food, vegetables, etc., to be kept cool. This practice has many objections, such as that everything so positioned gets wet, breakage and spillage due to ice dislocations and the insecure foundation for bottles, dishes, etc. of the usually very uneven bottom of the ice compartment, and the necessity for removing and replacing these articles at the time the ice chamber is to be filled with ice. It is a rather unsanitary practice. One object of these improvements is to maintain the ice chamber clean and preserve the food articles against loss and damage.

The receptacle 20, Figs. 3 and 4, is an open-ended housing-like structure of sheet metal having a flat and normally horizontal bottom 21, vertical side walls 22 and 23, and a top wall 24. Upper and lower ventilation openings 25 and 26 provide for circulation of air within the receptacle, and further circulation is afforded around the open ends. These openings 25 and 26 are on the side facing the ice in the ice chamber, and the pressed-out construction of the sheet metal, providing what are usually called louvers, protects the interior of the receptacle from the water of melted ice. The ice will often be packed fairly tightly in the ice chamber, with one cake on top of the other or with small pieces piled thereon and against the receptacles, and the receptacles should therefore be stout and strong. Ordinary galvanized sheet iron of say No. 14 gauge would be appropriate. In order further to strengthen the construction the top wall 24 and the side wall 22 may have ribs as 27 and 28 formed therein respectively.

Since the bottom of the ice receptacle is usually quite irregular and slanting I prefer to support the receptacle in the refrigerator chamber at one of its side walls, as clearly to be seen from Fig. 4, and to support it for ready movability, and also

whereby it may not be removed through the outer refrigerator door 14 when the inner door 13 is closed. Means for so supporting the receptacle are shown as a metallic bar 30 secured by screws 31 (Fig. 8) to the vertical side wall A. The bar 30 carries near each end a stud 32 having a head 33 and a cylindrical part 34 between the head 33 and the plate 30.

10 Turning to Fig. 7 it will be noted that the side wall 23 of the receptacle is provided with a pair of bayonet slots 35 having an enlarged part through which the head 33 may pass and a constricted part more closely fitting the shank 34 of the stud. In Fig. 7 parts have been omitted at the right-hand end to show the construction of this slot 35, and it will be observed that I provide an upward enlargement of the slot at 35^a so 15 that the receptacle will become somewhat locked in its normal position, subject to longitudinal movement in one direction under a little pressure.

It is to be noted that these slots 35 are so 20 directed that the receptacle must be moved bodily in the direction of the inner door 13 to bring the fixedly-secured heads 33 of the studs opposite the enlargements at the ends of the slots respectively. The receptacle is 25 so long that its inner end is so close to the door 13 that when this door is closed the receptacle may not be moved far enough inward for detachment, and, accordingly, one opening the outer door 14 may not remove 30 the receptacle.

In order that the receptacle may hang with its side walls vertical I have shown 35 projections 36 (Figs. 1 and 4) pressed in the metal at the lower portion of the side wall 23 to act as spacing elements to compensate for the thickness of the bar 30.

Within the receptacle 20 and resting on the bottom wall 21 thereof there is a shallow open-top drawer 40 shown complete in 40 Fig. 5. It has a bottom 41, shallow side walls 42, a rear end wall 43, and a front end wall 44. The front end wall extends laterally beyond the sides to serve as a stop to prevent the drawer from being withdrawn 45 in the direction of the outer refrigerator door 14.

A vertical partition plate 45 rests on the bottom of the drawer and is made stable by a pair of triangular side extensions 46 bent 50 over from the sheet metal of the partition 45. The bottom edges of these extensions 46 serve as a base for the partition. This partition 45 divides the drawer and also the hollow interior of the receptacle 20 into two 55 compartments. Fig. 4 shows that the partition 45 extends close to the top wall 24 of the receptacle, and that its dimensions otherwise are such as to protect what may be on the inner side thereof.

60 I have provided means for locking the

partition in place and for its adjustability in the drawer. These means comprise a plurality of holes 47 in the side walls 42, a pintle 48, secured as by riveting, on each of the side extensions 46, these pintles projecting through oppositely-disposed ones of the holes 47 in the side walls 42. These side extensions 46, being of sheet metal, may be sprung inward by hand sufficiently to release the pintles 48, whereupon the partition 65 may be adjusted to some other relative position in the tray or drawer.

In the use of the device tradesmen having access to the outer door 14 may deliver milk, groceries, etc. into the receptacle at one end and the housewife on opening the inner door 70 may remove such articles; and she can put food articles into the inner end of the receptacle where they will receive the desired refrigeration, all while maintaining the ice compartment free of such articles. As illustrated and described herein the device 75 preferably includes a sliding tray or drawer extending from end to end of the receptacle and covering substantially its entire bottom area, and in such case the articles would be delivered into the tray. The partition 80 provides security for the food articles placed into the tray from the inner door 13. When the housewife desires to remove what has 85 been inserted in the outer compartment, or for a more free reference to what is in the inner compartment, the drawer is pulled out to the desired extent, and may be withdrawn entirely, as for cleaning it and the inside of the receptacle without bodily removing 90 the latter.

In case of spillage from dishes or bottles 95 placed in the tray the refrigerator as a whole is not soiled and contaminated thereby, as all such spillage remains in the tray, and the tray may readily be cleansed.

100 A valuable feature of the construction is that it may be made and installed quite cheaply.

105 While this device would have advantages in other constructions of refrigerator than the specific one shown, it is peculiarly beneficial in that construction in view of its importance in connection with outside deliveries.

I contemplate as being included in these 110 improvements all such variations, changes and departures from what is thus specifically illustrated and described as fall within the 115 scope of the appended claims.

I claim:

1. The combination with a refrigerator 120 having walls forming a chamber provided with an inner and an outer doorway for access thereto and a door for each doorway, of means forming a housing-like open-ended receptacle for food articles in said chamber, the receptacle being of such length and being so positioned that its ends are ad- 125 130

- 5 jacent to said doors respectively when the doors are closed.
2. The combination of claim 1 hereof in which said receptacle has ventilation openings.
3. The combination of claim 1 hereof in which there are means holding said receptacle readily removable upon a wall of the refrigerator chamber.
- 10 4. The combination of claim 1 hereof in which said receptacle is readily removably held in its normal position by means coacting with the inner door and rendered operable for removal of the receptacle by opening said inner door.
- 20 5. The combination with a refrigerator having walls forming a chamber provided with two oppositely-disposed doorways and a door for each thereof, of an open-ended housing-like receptacle for food articles within the chamber, the receptacle being of such length and being so positioned that its ends are adjacent to said doors respectively when the doors are closed, and an open-top drawer in the lower portion of said receptacle.
- 25 6. The combination of claim 5 hereof in which said receptacle has ventilation openings therein.
- 30 7. The combination of claim 5 hereof in which said drawer covers substantially the entire bottom area of the receptacle and has an upstanding partition dividing the receptacle into a forward and a rear compartment.
- 35 8. The combination of claim 5 hereof in which there is an upstanding partition carried by the drawer and dividing the receptacle into a forward and a rear compartment, said partition being mounted adjustably to vary the size of said compartments.
3. The combination of claim 5 hereof in which said receptacle is mounted on a side wall of the ice chamber by means coacting with the inner door and which provide for ready removability of the receptacle only when the inner doorway is open.
10. A receptacle of the character described having a substantially flat bottom, upstanding side walls, and a top wall, and being formed of sheet metal, the receptacle being relatively long and of substantial width, an open-top drawer occupying substantially the entire bottom portion of the receptacle and being slidable therein and withdrawable in one direction only, the drawer having shallow side walls.
- 50 11. The combination of claim 10 hereof in which said drawer has an upstanding partition provided with side extensions having bottom edges forming a base and being adapted to yield inwardly under lateral pressure, one of the side walls of the drawer having openings longitudinally arranged to accommodate a pintle, a side extension of the partition having a pintle adapted to register successively with each of said openings, the arrangement and construction providing that the partition may be adjusted longitudinally in the drawer and held by the pintle.
- 60 12. The combination with a refrigerator having walls, including side walls, forming an ice chamber provided with a door opening for access and a door therefor, of a sheet-metal housing-like receptacle in said chamber and extending substantially from front to rear thereof, the receptacle being open at its front end adjacent to said door and being adapted to contain articles of food.
- 65 13. The combination of claim 12 hereof in which there is a drawer in the receptacle slidable in the direction of the refrigerator door.
- 70 14. The combination of claim 12 hereof in which there are means including a bayonet slot connection for holding said receptacle readily removably upon a side wall of the ice chamber, the bayonet slot connection being arranged whereby the receptacle must be moved substantially horizontally to be released for removal.

OTTO STRUFE.
